Attorney

UNITED STATES PATENT OFFICE.

EDWARD T. CURRAN, OF DETROIT, MICHIGAN.

WATER-HEATER.

1,335,560.

Specification of Letters Patent. Patented Mar. 30, 1920.

Application filed February 20, 1918. Serial No. 218,212.

To all whom it may concern:

Be it known that I, EDWARD T. CURRAN, who am a citizen of the United States, residing at Detroit, county of Wayne, State 5 of Michigan, have invented a certain new and useful Improvement in Water-Heaters, and declare the following to be a full, clear, and exact description of the same, such as will enable others skilled in the art to 10 which it pertains to make and use the same, reference being had to the accompanying drawings, which form a part of this specification.

This invention relates to water heaters 15 ordinarily termed as "instantaneous water heaters" to supply a quick or instantaneous hot water supply or for a hot water heating system, and under certain conditions may be utilized as a steam generator, and it is 20 the object of the invention to provide a heater of this character which is simple and cheap in construction, and to provide a novel combination and arrangement of parts to produce a heater which is highly efficient 25 in operation.

In the drawing accompanying and forming a part of this specification, Figure 1 is 30 a longitudinal view, partly in section, of a water heater showing an embodiment of my invention.

Fig. 2 is an enlarged sectional view of a portion of the heater to show the internal arrangement of the same and the connection of one element to another element thereof; 35 and

Fig. 3 is a cross sectional view taken on the line 3—3 of Fig. 2 looking in the direction of the arrow.

Similar characters of reference designate 40 like parts throughout the different views of the drawing.

In carrying out the embodiment of the invention shown in the drawing I provide a pair of nested and spaced apart cylindrical shells 4, 5 with the lower end of the outer shell flanged inwardly, as at 6, and welded to the projecting end of the inner shell to provide a water carrying jacket A. The lower end of the inner shell 5 is open and is 45 arranged for a burner B for a gaseous fuel. The space within the shell 5 constitutes a combustion chamber having an outlet at the top for the products of combustion comprising a pipe E passing through openings 50 in the shells and welded thereto, said pipe also serving to maintain the shells in spaced

relation, and may be connected to a flue or chimney, not shown.

A water heating unit is inclosed within the water jacket and comprises a series of 60 superposed, spaced apart and connected truncated cone shaped annular water chambers or jackets, shown as four in number K, K', K² and K³, although a greater or less number of these chambers may be utilized 65 if desired. These chambers consist of spaced shells L, L' (Fig. 2) inclining downward and outward at an acute angle relative to the axis of the water jacket A with the outer wall of the chambers at the base 70 fitting preferably snugly to the shell 5 of the water chamber A.

The lowermost chamber K³ which is directly above the burner B has a clear and unobstructed opening therethrough, while 75 the chambers K², K' and K are each provided with a circular though comparatively flat water chamber N located concentric within the enlarged ends of said chambers and connected with the chambers in water 80 circulation at substantially diametrically opposite sides by hollow legs M, M'. These chambers N, P, P' form baffles and obstructions for the free passage of the heat of combustion through the interior of the 85 chambers and cause the same to take a tortuous passage about the said chambers through the combustion chamber.

The chamber K³ is connected in water circulation with the chamber K² by pipes 90 M, M', similar to the manner as shown in the connection of the chambers K' and K in Fig. 2, though only the connection M can be seen in Fig. 1, the pipe M' being diametrically opposite. The pipe M communicates with the annular chambers K³ and K², while the pipe M' communicates with the annular chamber K³ and with the circular chamber N of chamber K² as shown in 95 Figs. 2 and 3.

The chamber K² is also connected in water circulation by means of the pipes M, M' with the chamber K', but which are located at right angles to the pipes connecting the chambers K³ and K², as clearly shown in 100 Fig. 1. The connecting pipe M' from the chamber K² communicates with the circular baffle chamber N of chamber K', while the pipe M' communicates with the annular water jacket of the chamber K'. The 105 chambers K and K' are connected in water circulation in a similar manner except that 110

- the connecting pipes are located substantially at right angles to the pipes connecting the chambers K' and K^2 , and similar to the connection of the chambers K^2 and K^3 .
- 5 A circular and comparatively flat water chamber R is located above and spaced from the uppermost water chamber K and connected in water circulation therewith by pipes Q extending in a vertical direction,
- 10 the diameter of this chamber being substantially the same as the smaller end of the cone shaped chambers. The heating unit built up by the respective annular water chambers is connected to a source of hot
- 15 water supply, or in circulation with a hot water heating system, by a pipe D leading from the circular chamber R and extending through the water chamber A . The heating unit is connected to a source of water
- 20 supply by a pipe C shown as leading through the water jacket A and connected to the lowermost chamber K^3 of the heating unit. The passage of the water through the chambers of the heating unit is substantially
- 25 as indicated by the arrows in Fig. 1.
- To provide a supply of water to the jacket A and induce a circulation of the water through such jacket and the heating unit, the chamber or jacket A is connected to the heating
- 30 unit by a pipe F leading to the chamber K^2 and a pipe R' leading to the chamber K^3 , although it is evident that each of the chambers constituting the water heating unit could be connected in circulation with the
- 35 jacket A . The water jacket also has a connection with the outlet pipe D by a port G in said pipe in communication with the jacket A . The water jacket A may also be provided with a drain cock H .
- 40 The cone shaped annular chambers and the connecting pipes M , M' are preferably made of an integral structure by welding the parts together and thereby providing an inexpensive and efficient water heater.
- 45 In operation and utilizing the heater for a hot water supply the annular cone shaped chambers of the heating unit and the jacket A are maintained in connection with a water supply through the connection C , which may be controlled by a stop cock, not shown.
- 50 The fuel is then ignited at the burner B the products and heat of combustion passing up through the chamber K^3 into and through the space between the next chamber K^2 and in such passage impinges against the hollow baffle member N , passing around said member and the pipes M , M' , as shown by the arrows in Fig. 2; thence they pass through the chamber K^2 to the
- 55 next chamber K' and in such travel pass around the pipes M , M' connecting said chambers and impinge against and pass around the baffle member N at the bottom of said chamber K' , and thence passing
- 60 through chamber K' and impinging upon the baffle member N of chamber K , and through said latter chamber K , whence they impinge against the chamber R and are deflected thereby around the pipes Q and the outlet pipe D to the space above said chamber R to the outlet flue E . By this tortuous passage of the heat and products of combustion practically all of the heat is absorbed by the different chambers of the water heating column or unit. When utilizing the
- 65 apparatus in connection with a hot water heating system after the heating unit and chamber A is filled with water they are shut off from the source of supply, the inlet C for the chamber K^3 being arranged as the
- 70 water return.
- 75 What I claim is:
1. In a water heater, an elongated and domed water jacket open at the bottom to constitute a combustion chamber; a burner for gaseous fuel within the opening at the bottom of said jacket; an outlet through the jacket for the products of combustion; a series of truncated cone shaped annular water chambers in superposed axial arrangement within the water jacket to provide a passage through the successive chambers for the heat of combustion; means to connect said chambers in water circulation with each other and the jacket; a water inlet to the lowermost of said annular water chambers; and an outlet for said chambers.
- 80 2. In a water heater, a water heating element comprising a series of axially aligned annular truncated cone shaped water chambers with the walls of all the chambers inclining in the same direction and at an acute angle to the axis thereof; means to connect said chambers in water circulation with each other, with the lowermost chamber having an unobstructed opening therethrough and the chambers superposed thereto and to each other having a circular chamber concentric therewith at the larger end with lateral legs connected to the chambers, and through which circular chamber a lower chamber is connected in water circulation with the next adjacent upper chamber.
- 85 3. In a water heater, a domed chamber to constitute a combustion chamber having an outlet for the products of combustion; annular cone shaped chambers arranged in superposed and spaced relation within the combustion chamber with the outer wall of the chambers at the base to lie contiguous to the wall of the combustion chamber; a water inlet to the lowermost of said cone shaped chambers; means to connect a lower cone shaped chamber in water circulation with the next adjacent upper chamber; and an outlet for said chambers from the uppermost chamber.
- 90 4. In a water heater, a domed cylindrical water jacket to constitute a combustion chamber having an outlet for the products
- 95
- 100
- 105
- 110
- 115
- 120
- 125
- 130

of combustion; annular cone shaped water chambers with the walls inclining at an acute angle to the axis thereof and arranged in axial superposed and spaced relation 5 within the combustion chamber; means to connect a lower cone shaped chamber with the next adjacent upper chamber; means to connect the chambers in water circulation with the jacket arranged to induce a circulation of water through the jacket, a water inlet to the lower cone shaped chamber; and an outlet from the uppermost of said chambers.

5. In a water heater, a domed cylindrical water jacket to constitute a combustion chamber having an outlet therethrough for the products of combustion; annular truncated cone shaped water chambers arranged in axial superposed and spaced relation 10 within the combustion chamber, the lowermost chamber having an unobstructed opening therethrough, and the successive upper chambers having a chamber extending transverse thereof at the base and in water 15 circulation with the annular chambers at substantially diametrically opposite points; a pair of pipes to connect a lower chamber with the next upper chamber, one pipe leading from the annular portion of the lower 20 chamber to the annular portion of the upper chamber, and the other pipe leading from the annular portion of the lower chamber to the transverse chamber of the 25 adjacent upper chamber; a water inlet to the lowermost annular chamber; and an outlet 30 leading from the uppermost chamber.

6. In a water heater, a domed cylindrical

water jacket to constitute a combustion chamber having an outlet therethrough for the products of combustion; annular truncated cone shaped water chambers arranged in axial superposed and spaced relation 40 within the combustion chamber, the lowermost chamber having an unobstructed opening therethrough and arranged for connection to a water supply, and the successive upper chambers having a chamber extending transverse of the base and in water circulation with the annular chambers at substantially diametrically opposite points, and 45 50 said transverse chambers of successive annular chambers extending at right angles; a pair of pipes leading from the top and diametrically opposite points of the respective annular chambers, one of said pipes being connected to the annular portion and the other to the transverse portion of the next adjacent upper chamber, and the pipes leading from the successive chambers being located at right angles to each other; a circular water chamber superposed to the uppermost annular chamber and connected in water circulation with said latter chamber; an outlet from the superposed chambers 55 from said circular chamber; means to connect the annular superposed chambers in water circulation with the jacket; and a burner for gaseous fuel arranged in the combustion chamber below the lowermost annular water chamber therein. 60 65 70

In testimony whereof I sign this specification.

EDWARD T. CURRAN.
